METHOD OF FORMING BOOKS

Frank J. Leyerle, Mechanicsville, N. Y.

Application April 13, 1935, Serial No. 16,122

1 Claim. (Cl. 11—1)

The invention relates to permanently bound books and a method for making same.

Books of the flat-opening type are illustrated and described but other styles of books are not precluded as the invention is applicable to books of various character. The flat-opening books particularly shown are of the type wherein the sheets and covers may be swung substantially 360° as in a stenographer's notebook.

10 In accordance with the present invention the collection of sheets and covers of the book is provided with a series of preformed perforations adjacent one of their edges. Binding wires or staples are passed through said perforations and formed into ring-like shapes while being passed through the perforations. After being introduced and formed they are held in position by the forming dies or other suitable means and are electrically welded in position. One of the important features of the present invention is the 20 fact of the binding means being electrically welded after the insertion thereof into the book.

Due to the electric welding the ring binding of books made in accordance with the present invention is of an absolute rigid and integral formation. This makes for a strong and firm construction and one that insures against any of the sheets escaping from the bound book.

The welded construction also provides perfectly smooth junctions thus making for an exceedingly neat and good looking book and one in which the sheets may be turned with the greatest of ease as there is no possibility of any obstructions being encountered.

35 In a number of types of ring binders the inherent resiliency of the metal is relied upon to maintain the binding means in its closed position. Therefore a comparatively hard wire must be used. Wire of this kind is hard to work and more costly 40 to use. By virtue of the electrically welded structure a softer and less expensive wire is advantageously utilized.

By the use of substantially true rings there will be no offset between the opposed sheets when 45 opened flatwise. A less number of perforations may be used and they may be spaced in any desired manner. In addition the sheets may be turned as freely and easily in one direction as in the other and the ring binding of the present 50 invention will not be distorted with ordinary handling.

Books such as stenographers' notebooks, composition books or other notebooks for students' use must retail at a low price. Economies in 55 production are therefore essential and the pres-

ent invention, in addition to producing a good appearing and excellently made book, particularly has this in mind.

Other objects and advantages will become apparent as this specification proceeds. Referring to the accompanying drawings forming a part thereof and in which preferred embodiments of the invention are illustrated:

Fig. 1 is a schematic view illustrating a method of assembling the book;

Fig. 2 is a detail perspective view showing one of the binding staples partially formed in the collection of sheets and covers;

Fig. 3 is a similar detail perspective view illustrating one of the binding staples completely formed and about to be electrically welded. In Figs. 2 and 3 which represent steps in the operation the instrumentalities for the forming and welding have been omitted;

Fig. 4 is a detail sectional view, the forming and welding instrumentalities being indicated in broken lines;

Fig. 5 is a detail sectional view showing the book in its finished condition;

Fig. 6 is an elevational view, a substantial part 25 of the body of the book being broken away;

Fig. 7 is a similar view of a modified construction; and

Fig. 8 is a perspective detail sectional view of another form of the invention.

Referring again to the drawings and particularly to Figs. 1 to 6 the reference numeral 10 designates diagrammatically a stepped assembling table to which collections of sheets 11, 12 and 13 are automatically fed in the direction of the arrows 14. While three collections of sheets are illustrated a greater or less number might be employed, the number of such collections depending upon the ultimate thickness of the book being manufactured.

At the rear edge of the assembling table are located standard punch presses 15. It will be noted the middle collection of sheets 12 is positioned on the assembling table somewhat forwardly of the collections 11 and 13. The piercing members of the punch presses 15 for the collection of sheets 11 and 13 are in line. Thus in their assembled relation as particularly shown in Fig. 4 the perforations 16 of the two outside groups of sheets are in line with each other and those of the middle group are offset in relation thereto. This arrangement as more particularly described hereinafter greatly facilitates the entering or insertion of the binding means. It will also be noted that the two covers 17 are placed 55

at the bottom of the third group of sheets 13 and the purpose of this arrangement will become apparent hereinafter. Dividing the book or pad into a number of groups or collections of sheets 5 is also conducive to better results as far as the punching is concerned as it is well known a thinner collection of sheets may be more effectively and advantageously punched than a collection of sheets of substantial thickness.

10 The assembling table is provided with automatic paper transfer means which comprises reciprocating slides 18. After the collections of sheets have been punched they are moved into superimposed relation to each other to the station indicated at 20. Here they are finally positioned between guides 21 and 22, held in position by a paper clamp diagrammatically indicated at 23, and moved to the station 24 where the automatic forming and electric welding of the binding means takes place. The instrumentalities for the forming and electric welding may be widely varied and are indicated schematically at 25 in Figs. 1 and 4.

20 The binding means illustrated in Figs. 1 to 6 comprises a staple 30 of conventional form having leg portions 31 and a connecting portion 32. Obviously any desired spacing may be obtained by varying the length of the connecting portions 32 and by varying the distance between the 30 staples.

In the operation a standard stapling head is used to form the leg portions of the staples into ring-like formation. As indicated in Fig. 2 the staple is forced upwardly in the direction of the 35 arrow 33 and dies 34 shown diagrammatically in Fig. 4 force the leg-portions through the staggered perforations 16 and form them into rings. It will be apparent from an inspection of Fig. 4 that the offset relation of the perforations of the 40 middle group of sheets in respect to the upper and lower groups greatly facilitates the passage of the staples through said perforations.

While the staples are held in place by the stapling head or forming dies the ends of the leg- 45 portions 31 are electrically welded at 35 to the connecting portions 32. One of the electrodes 36 as indicated in Fig. 4 may be introduced between the end of the pad and the staple and acts as a support for the staple when the other electrode 50 as indicated by the arrows 37 in Fig. 3 and broken lines 37 in Fig. 4 is entered to make the weld.

After the weld has been completed the lower

cover 17 is swung around substantially 360° and the connecting portions 32 of the staples lie between this cover and the collection of sheets as shown in Fig. 5. Thus when the book is closed only the rings are visible which greatly enhances 5 the appearance of the book. Obviously the same results would prevail if the two covers 17 were placed on top of the first collection 11 as when placed on bottom of the collection 13. After the book has been completed and is handled or jogged 10 slightly the sheets will assume an even and symmetrical appearance substantially as illustrated in Fig. 5. In Fig. 6 the staples or binding rings are shown in the position they would assume after the weld has been completed and before 15 the cover 17 has been swung around.

Referring to Fig. 7 in which a modified form is illustrated the binding means comprises a plurality of rings 40. In this form the binding wires are passed through the perforations 41 20 in a similar manner to that heretofore described in connection with the staples 30. A connecting member 42 is provided and the ends of the binding wires are simultaneously welded to each other and to the connecting member at 43. 25

Fig. 8 illustrates another form in which staples 50 are passed through apertures in a flanged plate 51 and are electrically welded at 52 to the flanges of said plate. The plate may be secured in any suitable manner to the back of a book. 30 The collection of sheets has been omitted in this view.

Changes in details of construction and arrangements of parts such as would occur to one skilled in the art are to be considered as coming 35 within the spirit of the invention and the scope of the appended claim.

I claim:—

A method of forming a permanently bound book from a collection of sheets having aligned 40 registering perforations along the edge to be bound, said method comprising forming the free ends of a staple-shaped binding wire into rings, passing said free ends through a pair of said 45 perforations adjacent one side of said book as said free ends are being formed into rings, welding the extremities of said free ends to the connecting portion of said staple-shaped binding wire while they are being held in position by said forming means, and successively treating other 50 staple-shaped binding wires in an identical manner until the binding is completed.

FRANK J. LEYERLE.
